UNITED STATES PATENT OFFICE.

ROBERT C. DANLY, OF CHICAGO, ILLINOIS, ASSIGNOR TO LUDWIG & LUDWIG, OF CHICAGO, ILLINOIS, A CORPORATION OF ILLINOIS.

SNARE-TENSIONING DEVICE FOR DRUMS.

1,354,028.

Specification of Letters Patent. Patented Sept. 28, 1920.

Application filed May 28, 1919. Serial No. 300,265.

To all whom it may concern:

Be it known that I, ROBERT C. DANLY, a citizen of the United States, and a resident of the city of Chicago, in the county of Cook and State of Illinois, have invented 5 certain new and useful Improvements in Snare-Tensioning Devices for Drums; and I do hereby declare that the following is a full, clear, and exact description of the same, 10 reference being had to the accompanying drawings, and to the numerals of reference marked thereon, which form a part of this specification.

This invention relates more specifically to 15 an improved type of snare tensioning device for side or snare drums, said device adapted to be set and held in an adjusted position, so that the snare strings may be simultaneously moved into an operative or an inoperative 20 position by means of a lever actuated cam mechanism.

It is an object of this invention to provide a means whereby the snare strings of a drum may be instantaneously thrown into a set or 25 release position.

Another object of the invention is the construction of a cam operated snare tensioning device for drums.

A further object of the invention is the 30 construction of a drum attachment capable of practically instantaneously converting a side drum into a snare drum, and vice versa.

It is also an object of this invention to equip a drum with a mechanism adapted to 35 adjust the snare strings of the drum and also affording a ready means permitting the adjusted snare strings to be moved into a release position.

It is furthermore an object of the invention 40 to provide a tensioning mechanism for the snare strings of a drum, said mechanism having means for holding the adjusting screw in an adjusted position against accidental release and also being provided with 45 a lever actuated cam for the purpose of moving the adjusted snare strings into a release or operative position.

It is an important object of this invention 50 to provide a drum snare string tensioning device of a simple and effective construction adapted to permit the adjusted snare strings to be moved into a release or active position with respect to the snare-head of the drum,

by simply actuating a slidably mounted cam control mechanism. 55

Other and further important objects of this invention will be apparent from the disclosures in the drawings and specification.

The invention (in a preferred form) is illustrated in the drawings and hereinafter 60 more fully described.

On the drawings:—

Figure 1 is a side elevation of a drum equipped with a snare tensioning device embodying the principles of this invention. 65

Fig. 2 is an enlarged front elevation of the tensioning device associated with a fragmentary portion of the drum, and showing the operation thereof in dotted lines.

Fig. 3 is an enlarged detail section taken 70 on line 3—3, of Fig. 2.

Fig. 4 is a section taken on line 4—4, of Fig. 2, showing parts in elevation.

Fig. 5 is a rear elevation of the cam control mechanism. 75

Fig. 6 is a fragmentary detail section showing the guide roller for the cam mechanism.

Fig. 7 is a fragmentary view of the snare string adjusting screw mechanism. 80

Fig. 8 is a plan view of a spring locking washer forming a part of the adjusting screw mechanism.

As shown on the drawings:

The reference numeral 1, indicates a drum cylinder made of wood or metal and having stretched across one end thereof a batter-head 2, and across the other end a snare-head 3. Drum hoops 4 and 5, are engaged around the cylinder to hold the drum heads 2 and 3, 90 in position. A plurality of adjustable clamping members 6, engage the drum hoops 4 and 5, for holding the material forming the drum heads stretched in position.

Mounted on one side of the drum cylinder in any suitable manner is a supporting bracket or plate (not shown) to which is secured one end of a plurality of snare strings 7, which extend downwardly in parallel relation to one another and are then directed 100 across the outer or bottom surface of the snare-head 3, and up along the opposite side of the drum cylinder as shown in Figs. 1 and 2. The other ends of the snare strings 7, are secured to an apertured plate or bar 8, 105 forming a part of a snare tensioning device.

embodying the principles of this invention and mounted upon the drum cylinder.

The snare tensioning device comprises a U-shaped or channeled attaching, supporting or mounting bracket 9, provided with a guide slot 10, in the front plate 11, thereof, and having integrally formed at right angles to the channel flanges apertured attaching lugs 12, adapted to receive screws or rivets to permit the supporting bracket to be secured in position on the drum cylinder. Integrally formed along each longitudinal margin of the front or slotted plate 11, of the supporting bracket 9, is an outwardly and inwardly directed guide channel 13, affording a guide groove, as shown in Fig. 3. The two guide channels 13, have the longitudinal margins thereof spaced apart to provide an opening or slot 14.

Pivottally mounted on the inner face of the supporting bracket plate 11, by means of a pivot pin 15, is a cam 16, provided with a curved slot 17, and having integrally formed thereon an arm or lever 18, which projects outwardly through one of the open sides of the supporting bracket 9. The cam lever 18, has a knob or handle 19, secured near the outer end thereof to facilitate operation of the cam. Projecting through the curved cam slot 17, is the reduced inner end of a roller 20, the enlarged outer end of which is positioned in the guide slot 10, of the supporting bracket 9. The roller 20, is rotatably mounted on a stud or pin 21, which projects through the slot 10, and has the outer end thereof secured to a plate 22, which is slidably mounted in front of the plate 11, and within the grooves of the channel guides 13. Integrally formed at right angles to the middle portion of the upper end of the plate 22, is an outwardly directed flange, lug or projection 23, of a width less than that of the slot 14.

Projecting upwardly through an opening 45 in the flange 23, is an adjusting screw 24, having a knurled head 25, secured on the upper end thereof. The lower portion of the adjusting screw 24, is threaded through a ball or knob 26, which is provided with 50 an integral extension 27, which projects through the opening 14, and has the end thereof rigidly secured to a slidable adjusting or tensioning plate 28. The tensioning plate 28, is slidably mounted in the grooves 55 of the channel guides 13, to the front of the plate 22. As clearly shown in Fig. 4, the adjustable snare string bar 8, is integrally formed at right angles to the lower end of the tensioning plate 28. The snare strings 60 7, may be looped through the apertures in the bar 8, or may be individually knotted if preferred to hold the strings in place. Rigidly secured or integrally formed near the upper portion of the screw 24, between the ball 26 and the flange 23, is a ring member

29, having seated thereon below the flange 23, a spring washer 30.

The operation is as follows:

With the snare strings 7, disposed across the snare-head 3, and attached to the adjustable bar 8, the controlling cam 16, is moved by means of the lever 18, into the full line or snare position shown in Fig. 2. To adjust the snare strings 7, the screw 24, is turned by means of the knurled head 25, thereby drawing the ball 26 upwardly, causing the adjusting plate 28, to slide upwardly in the grooves of the guide channels 13, and lifting the bar 8, therewith. Raising of the bar 8, of course, simultaneously tensions all 80 of the snare strings 7. The screw 24, is turned until the snare strings 7, have been sufficiently tensioned to produce the desired effect when the batter-head 2, of the drum is played upon. The spring washer 30, is 85 disposed between the flange 23, and the ring 29, and acts to hold the adjusting screw locked in an adjusted position against accidental jarring loose.

To remove the snare effect, it is only 90 necessary to swing the cam 16, by means of the lever 18, into the release position shown in dotted lines in Fig. 2. This operation causes the roller to rotate and move downwardly in the slot 10, since the reduced end 95 of the roller is engaged in the curved cam slot 17. Downward movement of the roller acts to slide the plate 22, downwardly and also the adjusting plate 28, which is locked with the flange 23, by means of the ball 26, 100 and the adjusting screw mechanism. The string bar 8, is thus moved downwardly into release position, thereby simultaneously relaxing the tension on the snare strings 7. By throwing the cam lever upwardly the 105 drum is almost instantaneously converted into a snare drum, with the strings properly tensioned to produce the desired sounds when the drum batter-head is beaten or played.

The adjusting screw mechanism is very easily set as already described, and is locked in an adjusted position by the locking washer 30. The lever handle 19, affords a convenient means for operating the controlling cam 16, to simultaneously move the strings 7, into a snare or into a release position, without any danger of the strings becoming tangled, as is often the case when the snare strings or drums are being adjusted by the methods at present in use.

I am aware that numerous details of construction may be varied through a wide range without departing from the principles of my invention and I therefore do not pur- 115 pose limiting the patent granted otherwise than necessitated by the prior art.

I claim as my invention:

1. A snare tensioning device comprising a slotted support, a slotted cam mechanism 130

- 5 pivotally mounted thereon, a slidable member mounted on said support, a roller mounted thereon and engaged in the slots in said support and in said cam mechanism, a
 10 string tensioning member slidably mounted on said support, an adjusting screw mounted on said slidable member and connected with said string tensioning member, said adjusting screw adapted to be actuated to tension snare strings connected with the string tensioning member, and locking means on said adjusting screw for holding the same in an adjusted position, said cam mechanism adapted to be operated to cause
 15 simultaneous movement of the slidable member, the adjusting screw and the string tensioning member to move the snare strings from an adjusted tensioned snare position into a release position.
- 20 2. A tensioning and control device for snare drums comprising a support, a slid- able snare supporting plate, a tensioning screw connected to said plate, a second slid- able plate coöperating with said screw and
 25 control mechanism connecting said second plate to said support.
3. In a snare tensioning device, a slidable snare supporting member, an adjusting member operatively connected thereto, a
 30 support, and means slidably and pivotally coöperating with said support to control said snare supporting member.
4. In a snare adjusting and controlling device, a pair of relatively slidable plates, an adjusting screw operatively connected with one of said plates and coöperating with the other, a support, and means pivoted to said support for controlling said
 35 slidable plates.
- 40 5. A snare adjusting mechanism, a sup- port, and means pivotally and slidably connected to said support for varying the position of said mechanism.
6. A snare adjusting mechanism compris-
 45 ing a plurality of relatively movable mem-
- bers, means for moving one of said members relative to the other, a support, and a device pivotally and slidably connected to said support and coöperating with said mechanism for controlling the position of said mecha- 50 nism.
7. In a snare adjusting and controlling device, a slidable snare supporting member, an adjusting device operatively connected thereto, a support, and means coöperating 55 with said device and support for controlling the adjusted device, said means including a cam member pivoted to said support and a slidable member operated by said cam mem-
 60 ber.
8. In a snare adjusting tensioning device, a support having a guide slot, a slidable snare supporting plate, an adjusting screw connected to said plate, a cam member hav-
 65 ing a slot, pivoted to said support, and a 65 slidable member coöperating with said screw and having a projection extending through said slots for actuation by the cam member.
9. In a snare adjusting and tensioning 70 device, a pair of relatively slidable mem- bers, an adjusting device operatively asso- ciated therewith, a support, a cam member pivoted to said support, and operatively connected to said slidable members. 75
10. In a snare adjusting and tensioning device, a pair of slidable plates, an adjust- ing device operatively associated therewith, a support having a guide slot, a lever hav-
 80 ing a cam slot pivoted to said support, and a member connected to one of said slidable plates and extending through said slots.
- In testimony whereof I have hereunto sub- scribed my name in the presence of two sub-
 scribing witnesses.

ROBERT C. DANLY.
